To all whom it may concern:

Be it known that I, Hans Sluizer, a subject of the Kingdom of The Netherlands, residing in Nutley, county of Essex, State of New Jersey, have invented a new, original, and ornamental Design for a Textile Fabric or Similar Article, of which the following is a specification, reference being had to the accompanying drawing, forming part thereof.

The figure is a plan view of a textile fabric showing my new design, embodying one com-

plete design unit, each unit containing a single crescent.

The design is composed of a series of stars emanating from a crescent, suggesting the appearance of moon beams on a starry background, as shown.

I claim:

The ornamental design for a textile fabric or similar article, as shown and described.

HANS SLUIZER.
